BUSHINGS FOR CONNECTERS

Dwight W. Pond, Terryville, Conn., assignor to
 National Engineering Corporation, Terryville,
 Conn., a corporation of Connecticut

Application January 22, 1931, Serial No. 510,374

4 Claims. (Cl. 247—43)

This invention relates to bushings, and more particularly to bushings for connectors which are used to couple conduit, loom, flexible armored cable, and the like, to outlet boxes and similar electrical fittings.

Such cable connectors have been used for a long time and their design is more or less standardized. They usually comprise a tubular body with a reduced neck portion attachable to an outlet box or the like and at its other end have a squeeze jaw or any other suitable clamping means which is normally used to hold the cable in the cable connector and hence in the outlet box or the like. Some of these connectors have been provided with an inwardly projecting flange or stop shoulder which extends part way into the bore, in order to limit the movement of the armored shell of the cable into the connector body and into the outlet box or similar fitting, and it has been proposed to use an insulating sleeve which is slidable within the armored shell and provided with a flange to engage the burred and sharp ends of the cable arm in order to protect the conductors against short circuiting and other damage. In such cases, the stop flange on the connector body also serves to keep the insulator sleeve within the armored shell once the cable clamp was tightened.

When the connector body was provided with this inwardly projecting stop flange, the end of the armored cable, or the insulating sleeve when the latter was used, were substantially enclosed so that it was impossible for a person to inspect the same to determine whether or not it had chafed the insulation on the conductors, or to be sure that the insulating sleeve was used.

In order to accommodate such examination, it has heretofore been proposed to provide radial slots across the connector body stop flange. But, with this provision, only a very superficial examination was possible for the construction was such that it was impossible to determine if a sleeve had been properly assembled to the cable armor because only the end of the cable insulating sleeve could be viewed. With the provision of these so-called peep slots it was possible for unscrupulous workmen with fraudulent intent to use a cheap plain washer instead of the insulating sleeve with a flange which is costlier and much slower to assemble. Such a washer would have all the appearances of the much more desirable, and in some places required sleeve, once it was assembled to the connector and outlet box.

This deception was possible in spite of a close examination by the electrical inspector or by the

owner for whom the work was being done, because once the connection was completed by the electrician, and especially after the wall was lathed and plastered, the end of the cable armor or anything carried thereby was permanently enclosed by the inwardly projecting flange on the connector, and to actually detect it, it was necessary to entirely disassemble the coupling and in cases remove the outlet box or similar fitting from the plaster wall, with the obvious inconvenience and cost.

Even if no deception was intended, the electrician would have to take the same steps and have the same inconvenience if he should find upon examination that he had inadvertently omitted an insulator sleeve.

All of these difficulties are obviated by the present invention and besides other advantages are obtained by providing a stop for the end of the armor of the cable, not on the neck of the connector body as heretofore, but on a cap which is threaded over the end of the connector and which, in one embodiment of the invention herein illustrated, also constitutes the lock nut for securing the connector to a wall of the outlet box, for with this arrangement, the mere removal or unscrewing of the cap from the connector body will completely uncover and disclose the end of the cable armor, and adjacent parts of the cable and any thing carried thereby without necessitating or requiring the removal of the connector body from the outlet box or the removal of the cable from the connector.

Further, this cap, since it is so easily removable, may be provided with a continuous annular stop flange if desired, but preferably has for the same purpose a plurality of arms so spaced that the end of the cable armor or whatever may be carried thereby may be superficially examined without removing the cap.

Other features and advantages will hereinafter appear.

In the drawing:

Figure 1 shows part of an outlet box with a cable connector attached thereto by the combined cap and lock nut of this invention, the latter being shown in section and the connector body being broken away at one end to more clearly show the cable and insulating sleeve.

Fig. 2 is an end view of a connector assembly with the cap of the present invention applied thereto.

Fig. 3 is a sectional view of a casting from which, according to the present invention, the combined cap and lock nut may be made.

Fig. 4 is an end view of the casting shown in Fig. 3.

Fig. 5 is a sectional view of the modified form of the present invention, similar to Fig. 3, which may be threaded on an automatic or continuous threading machine.

Fig. 6 is a view similar to Fig. 4, showing the combined nut and bushing after it has been threaded.

Fig. 7 is similar to Figs. 5 and 6 but shows the previously coaxially extending arms forced inwardly to provide a flange against which the cable armor is stopped.

Fig. 8 is a perspective of the combined nut and bushing shown in Figs. 3 and 4, after the flange has been formed, looking at it from the top.

Fig. 9 is a perspective view of the bushing shown in Fig. 8, looking at it from the bottom.

Fig. 10 is a sectional view showing another embodiment of this invention wherein the cap and lock nut are made as separate pieces.

Fig. 11 is a perspective view of the cap shown in Fig. 10.

In the embodiment of the invention disclosed herein, there is applied to a cable, a connector 12 of rather conventional design comprising a threaded neck 13 which extends through a knock-out hole 14 in the outlet box 15 or any similar fitting until a shoulder 16 thereon engages the outer margin of the hole where it is usually held in place by a flat nut such as the nut 27 shown in Fig. 10. The other end of the connector projects outwardly from the outlet box and forms a clamp 17 which in the present showing comprises a spring jaw 25 which may be squeezed onto the conduit armored cable 18 or the like by tightening a screw 19. Any other suitable form of clamp, however, may be used.

Because connectors of this type and bushings of the present invention are used most often with flexible armored cable, this type of cable alone will be considered in the description which follows hereinafter, but it should be understood that the device of the invention may be used advantageously with loom, conduit and other cable protectors.

In preparing the flexible armored cable 18 for connection to the outlet box 15 and attachment to a switch or any similar receptacle usually placed in outlet boxes, it is customary for the electrician to saw across the helically wound metal strips 20 of the armor 21 as at 22 approximately two or three inches back from the end, after which this short section of armor is removed to expose the conductors 23, the ends of which are then stripped for connection to receptacle terminals.

In sawing across the cable at 22, a sharp edge or burr often remains, which if left unprotected might chafe or cut into the insulation or the conductors 23 and in some cases short circuit the entire system. To guard against this, it has heretofore been proposed to provide an insulating sleeve 24 at the end of the armor, preferably one with a tubular body 25 fitting within the armor 21 and having an integral flange 26 to engage over the end of the armor, as shown in Fig. 1. The insulation sleeve 24 when made continuous can be assembled by sliding the stripped ends of the conductors 23 through the hole therein, but usually it is split to be spread and fitted right over the side of the conductors.

After the cable is prepared in this manner, the conductors 23 are passed through a hole 28 in the connector body until the cable armor 21 is

properly positioned therein whereupon the clamp screw 19 is tightened.

It has been usual to provide an inwardly projecting flange in the connector body hole 28 which would pass the conductors 23 but engage and stop the cable armor 21 and thereby limit its movement into the outlet box 15; and, in those cases where an insulating sleeve 24 is used, the stop flange on the connector body would locate the sleeve and prevent displacement of the latter once the cable clamp is tightened. But, as heretofore stated, this construction makes a substantially closed connector end that necessitates digging the outlet box out of the plastered wall and removal of the cable from the connector and outlet box if the electrical inspector or home owner wishes to be sure an insulating sleeve rather than a cheap and quickly assembled washer is used. Similar limitations prevail if a person tries to ascertain if the sleeve is still properly assembled to the cable armor 21, or if the electrician wishes to place or replace an insulator 24 after the connector is assembled to the outlet box 15 and after the walls are plastered. This is equally true even when the stop flange on the connector body is notched or slotted, for the slots only permit a superficial examination, as above pointed out.

According to the present invention, however, the connector neck 13 is not provided with a stop flange or, in fact, anything which would prevent complete inspection of the cable end or anything carried thereby. Instead, the present invention provides a separate article which may or may not be removed for inspection of the underlying parts as desired, and which may be added to some old forms of cable connectors long since installed, all without removing the outlet box or breaking the cable connection, as set forth more fully herein-after.

In its preferred form, the present invention provides, for the threaded neck 13 of the connector body, a cap 29 which has one end partially closed so as to provide stop means for engaging the end of the cable armor or insulating bushing carried thereby if the latter is used. This cap is provided with internal screw threads 30 fitting the external screw threads 31 on the neck of the connector so that it may be applied to the connector 12 after the latter has been inserted in the knock-out hole of the outlet box.

In one embodiment of this invention, that shown in Figs. 10 and 11, the cap 29 is intended for use on the connector body neck 13 without serving the function of holding the connector in the outlet box and for use in conjunction with the usual check nut, while in the form of the invention shown in Figs. 1 to 9, that at present preferred, the cap is made long enough to constitute a combined cap and lock nut serving the additional function of securing the connector body in the outlet box.

Referring now to the embodiment of the invention shown in Figs. 10 and 11, where the cap is intended for use with the usual check nut 27, the cap is preferably provided on its surface with notches 32 so that it may be driven on the neck 13 to the desired position by use of a spanner wrench or by inserting the bit of a screw driver and tapping the other end with a hammer.

The position to which the cap 29 shown in Figs. 10 and 11 may be driven depends upon the particular way in which it is to be employed. It may be made with very little length, so that it may be brought up firmly against the end of the armored cable, or an insulator carried thereby,

without first engaging the usual nut 27 on the neck, or it may be made longer so as to engage the nut in which case it will serve to lock the nut against casual removal. With the former arrangement, the connector body 12 may be clamped to the armored cable with the end of the armor protruding slightly beyond the neck 13 of the connector before the connector is inserted in the outlet box since the cap can be tightened against the end of the armor or the insulator carried thereby whether the latter protrudes slightly more or less than is desired.

Where the cap 29 is intended to engage the lock nut to prevent its casual removal, it is the better practice to fasten the connector body to the outlet box with the check nut 27, then apply the cap and drive it on until it firmly engages the check nut after which the cable end is pushed through the connector body until the end of the armor 21 or the insulator 24 carried thereby is in firm engagement with the stopping means on the cap at which time the screw 19 may be adjusted to clamp the cable in that position.

Although the invention may well be practiced as above outlined by having the cap and lock nut made in two separate parts, it is preferable for the sake of the economy effected thereby in the manufacture of the device, and because of its convenience in use, to make the lock nut and cap as an integral part, and in this way the double work of threading the two parts is obviated, and the electrician in making an installation need handle only one part or piece.

This preferred form of the invention is illustrated in Figs. 1 to 9 in which the cap is made longer than in Figs. 10 and 11 so that its rear edge engages the margin of the hole 14 in the outlet box and the exterior of the cap is provided with flat surfaces 33 like those of a nut for engagement by a wrench or the bit of a screw driver.

In either case, whether the cap is made to constitute a lock nut or to operate with a separate check nut, the stopping means for the end of the cable or an insulator carried thereby, may comprise a continuous annular flange 34 on one end of the cap, partially closing that end of the cap so that the conductors 23 will pass therethrough while the end of the armor 21 or the insulator 24 will be engaged by the same. If desired, this flange may be slit so that the end of the cable or the insulator may be superficially examined without removing the cap from the connector.

However, for reasons which will hereinafter appear, it is preferable that the stopping means be constituted by a plurality of arms 35 which project inwardly from the cap and which have between them spaces 36 through which the end of the cable armor or insulator may be superficially viewed.

In addition to permitting complete inspection of the end of the cable armor to see if an insulator bushing 24, which is often required by the electrical code, has actually been used, the cap of the present invention, when removed, makes the armor 21 and the conductors 23 accessible so that an insulating sleeve, which was inadvertently omitted when making the installation, could be placed on the conductors and slid into position under the end of the armor, and this operation can be performed without removing the armor, the connector or the outlet box, and without unsoldering the wires or disconnecting them from anything else because the cap after being unscrewed from the neck can be slid over the wires

to allow as much freedom as needed for inserting the split insulating sleeve.

In case the cap shown in Figs. 10 and 11 is designed to be brought into direct engagement with the check nut 27 to secure the latter against casual movement, and in the form of the invention shown in Figs. 1 to 9, the cap is made sufficiently long so that the stopping means, i. e. the arms 35 will not engage the end of the threaded neck 13 on the connector when the cap is secured in position, and may therefore be brought into firm engagement with the end of the armor or the insulator protruding somewhat beyond the end of the neck. Preferably, the space 37 provided between the end of the neck and the 15 arms is such that these parts will not engage whether the connector is used with an outlet box of light or heavy gauge metal.

The usual method of manufacturing a part like the cap 29 would be to form it in a screw machine or cast it as shown in Figs. 10 and 11, leaving sufficient stock to cut the thread as shown in Fig. 10 with a back-out tapping operation. Because these parts are used in very large quantities by the electrical trade, even small savings 25 are extremely important, and with this object in view, the present invention provides several methods of forming the cap so as to effect substantial economies in time and labor.

This is accomplished, in one form, according 30 to the present invention, by casting the flange arms 35 coaxial with the bore, as shown in Figs. 3 and 4 to permit casting a single thread 38 at the time the cap nut body is cast. By having the arms 35 extend coaxially in this manner 35 and providing a thread of less than one turn, it is possible to use a draw core in casting the cap. After the part is so cast the arms may be headed over to form the inwardly projecting flange 34 by peening, drop hammer or any other fast 40 forming operation, and in this operation the apertures 36 close and form the narrow peep slots as shown in Figs. 8 and 9.

Another method of forming the cap 29, within the scope of this invention, is to cast the body 45 as shown in Fig. 5 wherein flange arms 35 again extend coaxially, but in this case sufficient stock is left in the core at 39 to cut a female thread; and, because the arms 35 extend coaxially and are hence clear of the bore, it is possible to tap 50 this cap in an automatic continuous tapping machine. After the tapping operation the arms may, as with the forms shown in Figs. 1 to 4, be bent or pressed together to provide the inwardly projecting flange 34 as shown in Fig. 7, 55 and also, the apertures 36 if made sufficiently wide form peep slots through which it is possible to view the end of the cable armor.

It should also be noted that the cap 29 is provided with a round head 46 which extends substantially to the wrench flats 33 to facilitate the operation of applying a wrench, by guiding the wrench to the flats, which is especially advantageous while working in the close confines of the 60 outlet box.

Other variations and modifications may be made within the scope of this invention and portions of the invention may be used without others.

Having thus described the invention, what is claimed as new and for which it is desired to obtain Letters-Patent, is:

1. In combination with a flexible armored cable, an insulator bushing on the end of the cable; 75

- a cable connector having a screw-threaded neck; an apertured outlet box into which said neck extends; a cap including a tubular body having an internal thread for engagement with a thread on the neck of the connector to anchor the connector in the aperture of the outlet box; and means for securing the cable to the connector with the end thereof adjacent the inner end of said neck; said cap having means partially closing the inner end thereof to act as a stop for the end of the cable armor and including a plurality of inwardly extending arms spaced from each other to afford peep slots for permitting superficial inspection of the end of the cable armor and insulator bushing carried thereby.
2. In combination with a flexible armored cable, an insulator bushing on the end of the cable; a cable connector having a screw-threaded neck; an apertured outlet box into which said neck extends; a cap including a tubular body having an internal thread for engagement with a thread on the neck of the connector to anchor the connector in the aperture of the outlet box; and means for securing the cable to the connector with the end thereof adjacent the inner end of said neck; said cap having a plurality of annularly spaced arms having notches between them; said arms being headed over before the cap is assembled to the body to form an inwardly projecting flange serving as a stop for the inner end of the armored cable; said notches being of such width and depth as to constitute a series of peep slots through which the end of the cable and an insulator carried thereby may be observed and inspected.
3. In combination with a flexible armored cable, an insulator bushing on the end of the cable; a cable connector having a screw-threaded neck; an apertured outlet box into which said neck extends; a cap including a tubular body having an internal thread for engagement with

a thread on the neck of the connector to anchor the connector in the aperture of the outlet box; and means for securing the cable to the connector with the end thereof adjacent the inner end of said neck; said cap having a plurality of annularly spaced arms having notches between them; said arms being headed over before the cap is assembled to the body to form an inwardly projecting flange serving as a stop for the inner end of the armored cable; said notches being of such width and depth as to constitute a series of peep slots through which the end of the cable and an insulator carried thereby may be observed and inspected, the length of the connector being less than that of the cap so that when the cap is applied a space is left between the end of the connector and the flange of the cap.

4. In combination, an armored cable; an outlet box; a cable connector having a tubular neck adapted to fit through a hole in the outlet box, a clamp on said connector adapted to engage and grip the armored cable passing through said tubular neck and into said outlet box; a flange on the connector adapted to engage and stop against the margin of the hole in the outlet box; a screw thread on the tubular neck; a lock nut removably fitting on said screw thread and adapted to pull said connector flange against the wall of the outlet box; an insulating bushing fitting within the end of the cable armor and curling over the edge of the latter; said nut having a plurality of annularly spaced arms extending toward each other and toward the axis of the hole to partially close the hole at one end and limit the movement of the cable into the box, the spaces between the annularly spaced arms providing peep slots permitting superficial inspection of the end of the cable after the connector is completely assembled and fully exposing the end of the cable when the nut is disconnected.
